REFRIGERATOR CABINET

Leonard W. Atchison, Schenectady, N. Y., assignor
to General Electric Company, a corporation of
New York

Application July 1, 1941, Serial No. 400,589

3 Claims. (Cl. 62—89)

My invention relates to refrigerator cabinets and more particularly to refrigerator cabinets of the domestic type.

It has been proposed to provide refrigerator cabinets of the domestic type with evaporators or cooling units which extend substantially the full width of the cabinet and which are located in the upper portion of the food storage compartment of the cabinet in order to provide a large volume of frozen food storage and also 10 adequate provision for the freezing of water, frozen desserts, and the like. One of the difficulties accompanying this type of construction is that when the evaporator is run at a low enough temperature to provide a good cold or 15 freezing compartment for such purposes, there is too great a cooling effect in the main food storage compartment and sweating or dripping from the under side of the evaporator and the evaporator door member, which may be utilized on the front end of the evaporator, is encountered under conditions of high humidity.

Accordingly, it is an object of my invention to provide a refrigerator cabinet with an evaporator of the above-mentioned type provided with means for regulating the exchange of cold air between the upper and lower portions of the cabinet.

It is a further object of my invention to provide a refrigerator cabinet having an evaporator of the above-described type which is provided with means for minimizing the condensation and collection of moisture on exposed under surfaces thereof and dripping thereof into the lower portion of the food storage compartment.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a side elevation, partly broken away, of a refrigerator cabinet embodying the principles of my invention; and Fig. 2 is a front partial view of the refrigerator cabinet of Fig. 1.

Referring to the drawing, I have provided a refrigerator cabinet 10 of the domestic type having suitable heat-insulated walls defining a food storage compartment 11, a suitable refrigerant evaporator 12 being disposed in the upper portion thereof. Below and adjacent the evaporator I have provided a pair of spaced-apart baffle 55

members or elements 13 and 14, respectively, the members being substantially co-extensive with the food storage compartment in width and depth. The lower member, however, is spaced from the rear wall and the upper member is spaced from the front wall so that warm air rising along the front of the storage compartment will be directed rearwardly below the lower member 13 and then upwardly and forwardly between the members 13 and 14 to the front of the compartment. The air then passes into heat exchange relation with the evaporator, is cooled, and then drops down through a space or passageway at the rear of the cabinet, replacing the warm air which rises at the front.

The walls of the refrigerator cabinet comprise an inner metallic sheet-metal liner 16 and an outer sheet-metal casing 17, suitable thermal insulating material 18 being disposed in the space therebetween. In order to minimize the conduction of heat between the inner and outer liners at the edges thereof, the space therebetween is closed by a breaker strip 19 preferably formed of a thermally resistant material which is also non-hygroscopic in character and which, for example, may be formed from one of the resinous materials known to the trade under the trade names, "Textolite," "Bakelite," etc.

In order to obtain access to the food storage compartment, there is provided an opening 20, a suitably heat-insulated door 21 being provided for closing the opening.

As stated above, a refrigerant evaporator 12 is disposed in the upper portion of the food storage compartment 11 and, as best seen in Fig. 2, is substantially co-extensive with the full width of the storage compartment 11. If desired, the evaporator may extend the full width of the compartment but I prefer to provide passages 22 on either side thereof for the circulation of the box air. Inasmuch as the remaining portions of the refrigerant circuit play no part in my present invention, it has been thought unnecessary to illustrate a complete refrigerant circuit. Any suitable refrigerating apparatus may be employed to withdraw gaseous refrigerant from the evaporator, compress the same, cool and liquefy the compressed refrigerant and return the liquid refrigerant to the evaporator, where the refrigerant will absorb heat from the food storage compartment and again be vaporized. There is provided a door 24 for closing the open front end of the evaporator. The door 24 is hingedly supported in any suitable manner, as adjacent the front edge of baffle member 14. The upper edge

of the evaporator door is spaced from the top wall of the compartment 11 to provide an air passage 25 over the top of the door.

I have provided baffle means for eliminating any opportunity for moisture collecting on the surface of the evaporator from dripping into the lower part of the cabinet or onto articles stored therein, and also for permitting control of the amount of cold air circulating from the upper portion of the food storage compartment into the main food storage compartment. As best seen in Fig. 1, the baffle means comprises the pair of vertically spaced-apart substantially horizontal baffle members 13 and 14, preferably formed from sheet metal and suitably supported below the evaporator 12. In the form of my invention shown in the drawing, the upper member extends, in the lateral direction, the full width of the cabinet and rearwardly from a point immediately below the evaporator door, the rear edge thereof being provided with a downwardly extending portion 25a, the free end thereof being spaced from the rear wall 26 of the storage compartment 11 in order to provide an air passage 27 between the upper and lower portions of the cabinet. Inasmuch as the front edge of the evaporator is spaced inwardly from the door 21, there is provided an air passage 28 extending upwardly between the door of the food storage compartment and the evaporator door 24. The lower baffle member 13 also extends the full width of the cabinet in the lateral direction and extends rearwardly from immediately adjacent the compartment door to a point spaced forwardly from the end of the downwardly extending portion 25a of the upper baffle element, providing an air passage therebetween. In order to seal the space between the front edge of the lower member 13 and the door 21, I have provided a gasket 30 suitably secured to the front edge of the lower member 13 and bearing against the inner surface of the door 21 when the door is closed, thereby preventing air leaking up the surface of the door. The members 13 and 14 may be sealed at the sides thereof in any suitable manner as by gaskets, or by providing the members with flanges secured, as by welding, to the side walls of the compartment 11.

Inspection of Fig. 1 will show that the air cooled by thermal association with the evaporator 12 will descend along the rear wall 26 of the compartment through the passage 27, displacing the lighter and warmer air in the compartment 11, the warmer air, therefore, rising in the forward portion of the food storage compartment until it strikes the under surface of member 13. The warm air will then flow rearwardly along the under surface of the member 13 and then upwardly through the passage between the member 13 and portion 25a of the upper member 14 and then forwardly between the baffle members into the vertically ascending passage 28, upwardly across the evaporator door 24, over the top thereof and then generally downwardly in thermal relationship with the evaporator 12. As already described, this movement of air will, under normal conditions of operation, raise the temperature of the member 13 sufficiently high to avoid the formation of moisture thereon, in other words, the temperature of the member 13 will be raised above the dew point.

The flow controlling member or damper 15 for regulating the amount of cold air flow may be secured to close the passage 27 in any suitable manner. I have illustrated the damper as being

pivotedly connected to the free end of the portion 25a of the upper member as indicated by the numeral 31. The control member 15 may be either manually or thermostatically operated. When the control member is in position to close passage 27, the baffle member 14, door 24, the side and rear walls of the storage compartment and member 15 provide a cold air trap which tends to prevent the circulation of cold air.

Inasmuch as an evaporator for the aforementioned purposes is intended to operate at a relatively low temperature, and because of its size, a relatively large cold area will be exposed to relatively warm air, a certain amount of condensation of the moisture entrained with the air may take place on the surfaces of the evaporator and the door 24 as well as on the surfaces of the upper member 14. In order to catch any such drip water which may accumulate from these sources, I have provided means for collecting such water. The lower member is provided with means for catching moisture collecting on the outside of the door 24, the lower side of member 14 and portions of the compartment walls. As illustrated, the member 13 is dished, as indicated by the numeral 32 and slightly tilted to one side or otherwise arranged so that the moisture accumulating in the baffle proper can be drawn off by means of a conduit 33 into a drain channel 34 from which the moisture may be withdrawn from the cabinet through a conduit 35. Any moisture falling on the upper surface of the upper member 14 and compartment side walls will be directed rearwardly and then downwardly along the rear wall of the compartment or across the damper 15 into the drain channel 34. The upper member also should be tilted or otherwise arranged to direct the moisture as described. While I have illustrated the drainage channel 34 as extending the full width of the food storage compartment 11, it will be understood that the members 13 and 14 may be so formed as to make it possible to use a drain channel of different construction.

Modifications will occur to those skilled in the art. For example, the elements or members 13 and 14 may be co-extensive with the depth and width of the storage compartment and may be provided with air passages or openings therethrough adjacent opposite edges thereof. I therefore aim in the appended claims, to cover all such changes and modifications as fall within the true spirit of my invention.

What I claim as new and desire to secure by Letters Patent of the United States is:

1. In a refrigerator cabinet having a food storage compartment, an access opening to said compartment and a door member for closing said opening, an evaporator of the type having an opening in the front wall thereof and a door for closing said opening, said evaporator also being adapted to be operated at a relatively low temperature for cold storage and the like and also being disposed in the upper portion of said compartment and extending substantially the full width thereof but being spaced from said compartment door and the rear wall of said compartment, the top of said evaporator door being spaced from the top wall of said compartment, a pair of vertically spaced-apart, substantially horizontal, baffle members adjacent and below said evaporator, the upper member extending laterally the full width of said compartment and rearwardly from said evaporator door, the rear edge portion thereof being provided with a down-

wardly extending portion spaced from said rear wall, the lower member extending laterally the full width of the compartment and rearwardly from immediately adjacent the compartment door, the rear edge thereof being disposed forwardly of said downwardly extending portion, whereby warm air rising along the compartment door will be directed rearwardly by the lower member, upwardly and forwardly between the members, upwardly between the compartment door and the evaporator door, over the top of said evaporator door and rearwardly and downwardly across said evaporator in thermal association therewith, the cooled air descending downward through the space between the downwardly directed portion and the rear wall of said storage compartment.

2. In a refrigerator cabinet having a food storage compartment, an access opening to said compartment and a door member for closing said opening, an evaporator of the type having an opening in the front wall thereof and a door for closing said opening, said evaporator also being adapted to be operated at a relatively low temperature for cold storage and the like, and also being disposed in the upper portion of said compartment and extending substantially the full width thereof but spaced from said compartment door and the rear wall of said compartment, said compartment door, said evaporator door and the side walls of the compartment providing a first vertically disposed air passage, the top of said evaporator door being spaced from the top wall of said compartment for providing a second air passage, a pair of vertically spaced-apart, substantially horizontal, baffle members adjacent and below said evaporator, the upper member extending laterally the full width of said compartment and rearwardly from said evaporator door, the rear edge portion thereof being provided with a downwardly extending portion spaced from said rear wall to provide a third air passage, the lower member extending laterally the full width of the compartment and rearwardly from immediately adjacent the compartment door, the rear edge thereof being disposed forwardly of said downwardly extending portion, whereby warm air rising along the compartment door will be directed rearwardly by the lower member, upwardly and forwardly between the members, upwardly through said first air passage, over the top of said evaporator door and across said evaporator in thermal association therewith, the cooled air descending downwardly through said third passage into said compartment at the rear thereof, and means associated with said lower member for collecting any moisture which may be condensed out of the circulating air and deposited

in thermal association therewith, the cooled air descending downwardly through said third passage into the lower portion of said compartment at the rear thereof, and means associated with said third passage for regulating the amount of cooled air flowing through said third passage and hence the temperature of said food storage compartment.

3. In a refrigerator cabinet having a food storage compartment, an access opening to said compartment and a door member for closing said opening, an evaporator of the type having an opening in the front wall thereof and a door for closing said opening, said evaporator also being adapted to be operated at a relatively low temperature for cold storage and the like, said evaporator also being disposed in the upper portion of said compartment and extending substantially the full width thereof but spaced from said compartment door and the rear wall of said compartment, said compartment door, said evaporator door and the side walls of the compartment providing a first vertically disposed air passage, the top of said evaporator door being spaced from the top wall of said compartment for providing a second air passage, a pair of vertically spaced-apart, substantially horizontal, baffle members adjacent and below said evaporator, the upper member extending laterally the full width of said compartment and rearwardly from said evaporator door, the rear edge portion thereof being provided with a downwardly extending portion spaced from said rear wall to provide a third air passage, the lower member extending laterally the full width of the compartment and rearwardly from immediately adjacent the compartment door, the rear edge thereof being disposed forwardly of said downwardly extending portion, whereby warm air rising along the compartment door is directed rearwardly by the lower member, upwardly and forwardly between the members, upwardly through said first air passage, over the top of said evaporator door and across said evaporator in thermal association therewith, the cooled air descending downwardly through said third passage into said compartment at the rear thereof, and means associated with said lower member for collecting any moisture which may be condensed out of the circulating air and deposited above said lower element.

LEONARD W. ATCHISON.
